UNITED STATES PATENT OFFICE.

CLARENCE H. BATES, OF CHICAGO, ILLINOIS.

NON-REFILLABLE BOTTLE.

1,175,501.

Specification of Letters Patent. Patented Mar. 14, 1916.

Application filed March 30, 1914. Serial No. 828,136.

To all whom it may concern:

Be it known that I, CLARENCE H. BATES, a citizen of the United States, residing at Chicago, in the county of Cook and State 5 of Illinois, have invented certain new and useful Improvements in Non-Refillable Bottles, of which the following is a specification.

The object of this invention is to provide 10 an improved bottle which cannot be refilled without breaking a portion of the bottle, so that a wholesaler may easily detect any fraudulent refilling of his bottles.

In the accompanying drawings, Figure 1 15 is a vertical sectional view through a bottle embodying the features of my invention. Figs. 2 and 3 are detail views of one of the parts.

The preferred embodiment of my invention 20 is illustrated in the drawings and comprises a body portion 4 and a neck portion 5. A stopper closes the upper end of the neck 5 and comprises a solid inner part 6 and a yieldable sleeve 7 of cork or other suitable 25 material surrounding said part 6. On the upper end of the inner part 6 is an enlarged head 8 having an offset portion 9 which constitutes a discharge nozzle. Preferably the sleeve 7 has an outturned flange 7^a at its 30 upper end which lies between the head 8 and the upper end of the neck 5. The port 10 within the nozzle 9 communicates at its inner end with a chamber 11 from which a vertical port 12 leads to the lower end of the 35 inner part 6 of the stopper. The chamber 11 is offset with relation to the ports 10 and 12 for a purpose to be presently explained. The port 10 is controlled by a conical valve member 13 having a transverse opening 40 therethrough and having an operating handle 14 fixed to its upper end. The valve member 13 is held in place by a screw 15 seated in the lower end thereof and engaging in a countersink in the underside of the 45 head 8. It will be seen when the parts are in assembled relation this countersink is closed by the flange 7^a on the cork sleeve 7, so that the valve member cannot be removed.

A vertically disposed tube 16 is secured 50 to the lower end of the stopper member 6 and communicates with the port 12. The lower end of the tube 16 lies close to the bottom of the bottle. Within this tube is located a valve device arranged to permit 55 liquid to flow from the bottle up through the tube and out the discharge nozzle 9, but

adapted to prevent a reverse flow of liquid. In its preferred form this valve device consists of a cork or other yieldable sleeve 17 fitting within the tube 16 and carrying a central short tube 18. A flexible flap valve member 19 is fixed to the upper end of the sleeve 17 and closes the tube 18. Preferably, the tube 16 is tapered from its lower to its upper end and the valve device just described is driven tightly into place, so that it cannot be dislodged.

The offset chamber 11 is provided for the purpose of preventing a person from inserting a wire through the discharge nozzle 9 and downwardly through the port 12 and tube 16 to pick the valve member 19 open, so as to permit the insertion of fluid into the

The stopper member 6 has a port 20 leading upwardly from its lower end and then laterally to its periphery. Through this port air under pressure is forced into the upper end of the bottle on top of the liquid therein. The lower end of the port 20 is 75 controlled by a flexible flap valve member 21 which may be secured to the lower end of the sleeve 7. Said sleeve and the bottle neck 5 have openings 22 and 23 registering with the angular upper end of the port 20. 80 The opening in the bottle neck is flared outwardly and is provided with an annular groove 24 in its wall. A locking device consisting of a screw 25 seated in a plug 26 of cork or other suitable material lies in the 85 openings 22 and 23, and in the angular upper end of the port 20. This locking device prevents the stopper members 6, 7, 9, from being withdrawn from the neck of the 90 bottle.

In order to prevent the locking device 25, 95 26 from being withdrawn by unauthorized persons a quantity of cement 27, preferably of character which is not heat susceptible, is introduced in the flaring opening 23 after 100 the insertion of the locking device, the cement running into the annular groove 24 in the wall of the opening 23. A disk 28 is then placed in the outer end of the flaring opening, said disk having an undercut rib 105 29 at its inner side which sinks into the cement 27. After the cement has hardened the disk will be firmly locked in place and can not be removed except by breaking it. If desired, a transverse groove 30 may be 110 formed in the outer face of the disk 28 so that the disk may be broken by the ultimate

user (not the retailer) when he desires to withdraw the locking device 25, 26 so as to remove the stopper. If desired, a suitable monogram or other symbol may be placed 5 upon the inner side of the disk 28 or in any other desired position on the disk, so that the retailer cannot replace a similar disk after he has broken one to refill a bottle. By means of a monogram or symbol an agent of the 10 wholesaler will be able to tell immediately whether the original closing disk is still on the bottle and thus he can ascertain whether the bottle has ever been refilled. It will be seen that it is impossible to refill this bottle 15 without first breaking the disk 28.

In use, the bottle is originally filled in the ordinary way up to about the level indicated by the line *a*, and the parts 6, 7 and 14 are then inserted into the bottle. Air is then 20 forced into the bottle through the openings 23 and 22 and port 20 until a sufficient pressure is in the bottle to force all of the liquid therefrom when the valve 13 is opened. The flexible valve member 21 will 25 prevent the escape of air through the port 20. The locking device 25, 26 is now inserted and the cement 27 and disk 28 put in place. The bottle is then ready for the market. Whenever it is desired to withdraw 30 all or a portion of the contents of the bottle the valve member 13 is opened and the compressed air in the bottle will force the contents up through the tube 14 and out the discharge nozzle 9. Any attempt to refill 35 the bottle through the nozzle 9 will be ineffective because the valve 19 is normally closed, and will open only to pressure from the interior of the bottle.

I claim as my invention:

- 40 1. A non-refillable bottle comprising a body having a neck, a stopper closing said neck and having a discharge passage therethrough, a valve member controlling said discharge passage, a tube leading from the inner end of said passage to the bottom of the bottle, a valve device in said tube, said stopper having a second passage leading from its inner end and terminating on one side, the neck of the bottle having an opening registering with the last mentioned passage, and means occupying said opening and said passage for preventing withdrawal of the stopper.
- 45 2. The combination of a container having an outlet, a closure for said outlet, said closure having a passageway therethrough, a manually operable valve controlling said passageway, a tube communicating with said passageway and leading to a point close to the bottom of said container, the closure and the con-

tainer having registering passages through which compressed air may be introduced into the container, and locking means occupying the last mentioned passages in the container and the closure for preventing removal of said closure, said locking means including a portion which is non-removable except by breakage. 65

3. The combination of a container having an outlet, a closure for said outlet, said closure having a valved discharge passageway therethrough and having a second passage through which compressed air may be introduced into the bottle, the latter passage being provided with an inwardly opening valve to prevent egress of air, the container having an opening registering with the outer end of the latter passage, and means occupying the passage and the opening for preventing withdrawal of the closure from said outlet. 70

4. A bottle having a neck and a stopper fitting into said neck, said stopper having a valve-controlled discharge passage therethrough and having a second passage leading upwardly from the inner end thereof and terminating on one side, the neck of the bottle having an opening registering with the latter passage, a locking device seated in said opening and said passage for preventing withdrawal of the stopper, and means which is non-removable except by breakage for sealing said opening in the bottle neck to prevent access to said locking device. 85

5. The combination of a container having an outlet, a closure for said outlet, said closure having a discharge passageway therethrough, a tube communicating with said passageway and leading to a point close to the bottom of said container, a manually operable valve controlling the discharge of fluid through said passageway, a second outwardly opening valve controlling such discharge and positioned inwardly from said manual valve, said closure and the container having registering passages through which compressed air may be introduced into the container, an inwardly opening valve controlling the last mentioned passages to permit ingress but prevent egress of the air, and locking means occupying the last mentioned passages for preventing removal of said closure. 90

In testimony whereof, I hereunto set my hand in the presence of two witnesses.
